UNITED STATES PATENT OFFICE.

WILLIAM E. BAILEY, OF BEVERLY, MASSACHUSETTS, ASSIGNOR TO ARBETTER FELL-
ING MACHINE COMPANY, OF BOSTON, MASSACHUSETTS, A CORPORATION OF MAINE.

SEAM FOR SEWED ARTICLES.

1,069,097.

Specification of Letters Patent.

Patented Aug. 5, 1913.

Application filed December 22, 1908. Serial No. 468,850.

To all whom it may concern:

Be it known that I, WILLIAM E. BAILEY, a citizen of the United States, and resident of Beverly, county of Essex, State of Massachusetts, have invented an Improvement 5 in Seams for Sewed Articles, of which the following description, in connection with the accompanying drawing, is a specification, like letters on the drawing representing 10 like parts.

This invention relates to a seam for sewed articles designed to be made by machine, and more particularly for use in what is known as "padding" work wherein two 15 or more superimposed layers of fabric are united by blind stitches, or stitches which enter and emerge at the same face of the fabric. Padding work is required, to a large extent, in the manufacture of men's 20 and women's garments, in securing together and stiffening the various layers of fabric. In this work it is desirable to secure a comparatively wide seam that shall bind two or more layers of fabric together firmly without 25 showing on the exposed face of the garment. These rows of stitches are made close together over considerable surfaces, and hence a seam which can be made rapidly is desirable. It is also desirable that so far as possible 30 the seam shall simulate the work hitherto performed by hand. Such seams must also possess a certain amount of elasticity otherwise the work may not lie flat or conform to the shape of the garment 35 without breaking the threads.

The construction of seam of this invention is one which presents perfect elasticity especially in the direction of length of the seam where it is most desired; one in which 40 the appearance of the seam is similar in appearance to the work done by hand; one which may be rapidly performed by machine operation; one in which the layers of the fabric are firmly united at regular and 45 symmetrical intervals; and one in which two threads are employed so that it is adapted to be made upon the lock stitch type of machine. These and other advantages reside in the construction illustrated, and in 50 the invention embodied therein, which invention will more fully appear from the accompanying description and drawings, and will be particularly pointed out in the claim.

The drawings illustrate the preferred 55 form of the seam as adapted to be made

by a machine provided with a curved needle, a complementary thread carrying stitch-forming mechanism and a means for securing a vibration of the work support and the stitch-forming mechanism laterally with respect to each other and transversely of the line of seam or feed of the goods.

In the drawings, Figure 1 is a perspective view of the seam. Fig. 2 is a cross-section to show the position of the thread.

The seam herein illustrated is one designed to be made by a blind stitch sewing machine comprising a needle carrying a thread and a thread carrying looper co-operating therewith to interlock its thread with the loop of thread thrown out by the needle. Preferably the material is fed over a flat work support and the needle is a curved one so that at each stroke of the needle it will enter and emerge on the upper face of the fabric and throw out its loop to be passed through by the thread carrying looper, such for example as the rotary hook and inclosed bobbin case. A means is also provided for giving a relative shogging movement, or relative lateral displacement, transversely to the line of feed of the stitch-forming mechanism and the work support. Preferably the work support remains stationary and the lateral movement is given the stitch-forming mechanism bodily. Since the subject matter of this invention resides in the seam itself, and not in the machine, it is unnecessary here to describe further the particular instrumentalities employed.

The seam as illustrated in the drawing is shown as uniting two superimposed layers of fabric A and B. The needle thread is indicated at D and lies on the upper face of the fabric in a zig zag line running in the direction of the line of seam or feed of the goods, except at the bends or angles of the zig zag line where it is formed into loops E. These loops E lie transversely of and preferably at right angles to the general line of the seam or feed of the goods, and they enter the upper surface of the fabric at the bend or angles of the zig zag lines, pass into the lower layer and emerge again at the upper surface.

The looper or interlocking thread is indicated at F and also lies on the upper surface of the fabric in a zig zag line running parallel to the needle thread D and at a short

distance therefrom and consequently also extends in the line of seam or in the direction of the feed of the goods. This looper thread F passes through each of the 5 loops E and forms with said loops stitches. The locking or engaging point of the looper thread F with the loops E is located either at the upper surface of the upper layer of fabric as shown at the left hand end of Fig. 10 1 or beneath the upper surface as shown at the right hand end of Fig. 1, depending upon the tension which is placed upon the needle thread to draw the interlocking point back into the goods. It will thus be seen 15 that the stitches, or that portion of the thread embedded in the fabric, extends transversely of the line of seam, enter and emerge from the same or upper face of the fabric, and lie staggered in two parallel 20 rows while the threads which show upon the upper face of the fabric, viz: the needle and looper threads, extend in zig zag parallel lines a short distance apart in the general direction of the line of seam. This construction secures great elasticity in the direction 25

of the seam, presents an appearance simulating that of hand work, and produces a strong and durable seam such as is desired in this class of work.

Having fully described my invention, 30 what I claim as new and desire to secure by Letters Patent is:—

A seam for sewed articles comprising a plurality of superimposed layers of fabric, two threads lying upon one face of the fabric in parallel zigzag courses, the said threads being interlocked at intervals, one or both of said threads being formed into loops at the interlocking points and the said loops extending transversely of the line of 40 seam and entering and emerging from the same face of the fabric upon which the parallel threads lie.

In testimony whereof, I have signed my name to this specification, in the presence of 45 two subscribing witnesses.

WILLIAM E. BAILEY.
